UNITED STATES PATENT OFFICE.

CHARLES KÜHN, AND GEORGE ZAHN, OF ROCHESTER, NEW YORK.

SPRING-WHEEL.

1,101,082.

Specification of Letters Patent. Patented June 23, 1914.

Application filed March 27, 1914. Serial No. 827,589.

To all whom it may concern:

Be it known that we, CHARLES KÜHN and GEORGE ZAHN, citizens of the United States, and residents of Rochester, in the county of Monroe and State of New York, have invented certain new and useful Improvements in Spring-Wheels, of which the following is a specification.

This invention relates to vehicle-wheels of the type in which the hub and the rim are connected by means having provision for a spring-controlled yielding movement to compensate for inequalities in the road surface, or in the driving force applied to the wheel.

One object of the invention is to produce a wheel, of the type in question, in which springs and sliding-joints are employed in such a manner as to permit limited relative movement between the rim and the hub of the wheel in all directions in the plane of the wheel, while confining the parts rigidly against relative movement in other directions.

Another object of the invention is to so arrange the sliding joints between the relatively movable members of the wheel as to minimize or prevent the entrance of foreign substances, and to assist the lubrication of the joints.

To the foregoing ends we employ a construction in which a metal web, carrying the rim of the wheel, is arranged to slide, in all directions in the plane of the wheel, between two plates projecting from the hub of the wheel, and in which both the web and the plates are provided with spring-receiving recesses, these recesses, in one of said members, being substantially radial, and in the other of said members substantially concentric with the wheel. The springs in the several recesses are interconnected, by means in the form of slides movable in the recesses and articulated together in such a manner as to control the relative movements of the wheel-members through their engagement with the springs.

Other objects of the invention, and the features of construction by which they are attained, will be pointed out hereinafter in connection with the following description of the illustrated embodiment of the invention.

In the accompanying drawings:—Figure 1 is a partial side-elevation of a wheel embodying the present invention, with the web and one of the side-plates broken away in some parts to show the interior mechanism; Fig. 2 is a vertical section on the line 2—2

in Fig. 1; Fig. 3 is a partial section on the line 3—3 in Fig. 1; and Fig. 4 is a perspective view of one of the sets of connecting-slides.

The illustrated embodiment of the invention is a wheel comprising a web 5 arranged to slide between two side-plates 6 and 7. The plate 6 projects integrally from the hub 8 of the wheel, while the plate 7 is centered on and keyed to the hub, and is held in position, parallel to the plate 6, by means of bolts 10, the necessary space between the plates being secured by bosses 11, on their inner surfaces, surrounding the bolts as shown in Fig. 3. The inner surfaces of the plates, at their peripheral portions, are provided with facings 12 of fiber or other suitable material, to improve the bearing between the plates and the web 5. The space between the plates is such that they fit closely against the web, but permit it to slide freely between them in all directions, either radial or rotative. The web is illustrated as provided with a solid rim 13, but it will be understood that this rim may either support or be replaced by a tire-holding rim of any required form, to permit the employment of pneumatic or other suitable tires. The relative movements of the web and the plates are controlled by means of springs and slides. A series of radially disposed slides 14 are mounted in slots formed in inwardly projecting portions 15 of the web, and two springs 16 and 17, respectively, are disposed between each slide 14 and the inner and outer-ends of the corresponding slot, the slide being recessed from its ends to afford as much space as possible for these springs. Each slide 14 is provided with two laterally-projecting pivot-pins 18, upon which are pivoted two slides 19. The slides 19 are curved longitudinally, so that they may fit into slots formed in thickened portions 20 of the two plates 6 and 7, these slots being concentric with the plates. Springs 21 and 22, respectively, are interposed between each slide 19 and the ends of the recess in which it moves, the slides 19 being recessed inwardly from their ends to accommodate the springs.

The springs and the slides just described provide connections between the plates and the web which tend to hold these parts in the relative position illustrated in Fig. 1, but permit them to have relative movement, when subjected to the stresses of use, in all directions in the plane of the wheel. If, for

example, the wheel be subjected to an upward shock against the bottom of the rim, the web tends to move upwardly, and this causes the lowermost of the springs 17 to 5 be compressed, since the slides 19, by their engagement with the side-plates, prevent the slide 14 from moving upwardly with the web. Similarly, all of the springs 17 which are below the center of the wheel are more 10 or less compressed, but, in the case of each of the slides 19, which is not directly beneath the axis of the wheel, there is also a certain degree of movement of these slides 19, so as to compress, in each case, one of the 15 springs 21 or 22, while in the case of any of the slide-members which is approximately on the horizontal diameter of the wheel, the compression will occur wholly in the springs 21 and 22, while there will be no relative 20 movement of the web and the corresponding slide 14. In addition to yielding, in the above-described manner, to a force to which the wheel is subjected in any radial direction, it will be apparent that inequalities in 25 the driving motion which may be imparted to the hub of the wheel may cause the hub and the side-plates to perform a partial rotation relatively to the web and the rim of the wheel, this partial rotation being permitted 30 by compression of either the springs 22 or the springs 21, according to the direction of rotation, while the slides 19 move within the slots in the plates 6 and 7.

In order to avoid looseness and rattling 35 in the parts, all of the springs are preferably placed under some initial compression in assembling the wheel, so that when one spring is compressed the opposite spring shall expand so as to continually fill the 40 space provided for it. The arrangement of the parts is such, however, that this constant compression of the springs does not cause any substantial increase in friction 45 between the sliding members of the wheel.

It will be apparent that the arrangement 50 of the plates and the web of the wheel is such that as the wheel rotates the centrifugal force so produced tends to throw outwardly any foreign substance which may find lodgment 55 between the plates and the web, and also tends to prevent the entrance of such substance when the wheel is in use. For the same reason any lubricating substance packed within the moving parts of the wheel 60 will tend to flow or to be thrown outwardly, so as to constantly lubricate the engaging surfaces between the web and the plates near the peripheries of the latter, where the lateral strains are chiefly borne.

Our invention is not limited to the embodiment thereof hereinbefore described and illustrated in the accompanying drawings, but it may be embodied in various other

forms within the nature of the invention as it is defined in the following claims. 65

We claim:

1. A spring-wheel having, in combination with a hub and a rim; a web fixed to one of these parts; a pair of side-plates fixed to the other part and loosely embracing the web; the web and the side-plates being provided, in their adjacent surfaces, with slots arranged substantially at right-angles with each other; pivotally-connected slides located in the respective slots; and springs 70 adapted to retain each slide normally in central position in the respective slot.

2. A spring-wheel having, in combination with a hub and a rim; a web fixed to one of these parts; a pair of side-plates fixed to the other part and loosely embracing the web; the web and the side-plates being provided, in their adjacent surfaces, with slots arranged substantially at right-angles with each other; pivotally-connected slides located in the respective slots; and springs 75 adapted to retain each slide normally in central position in the respective slot, the springs being located within the slots at opposite ends of the slides. 90

3. A spring-wheel having, in combination with a hub and a rim; a web extending inwardly from the rim and provided with a series of substantially radial slots; a pair of side-plates extending outwardly from the hub, loosely embracing the slotted part of the web and one at least of them provided with substantially concentric slots in its inner face; a radial slide movable in each radial slot; a slide pivoted to each radial 100 slide and movable in the concentric slots; and coiled compression-springs located in the slots and engaging opposite ends of each slide. 95

4. A spring-wheel having, in combination 105 with a hub and a rim; a web extending inwardly from the rim and provided with a series of substantially radial slots and a series of intermediate outwardly-extending recesses; a pair of side-plates extending outwardly from the hub, loosely embracing the slotted part of the web, and one, at least, of them provided with substantially concentric slots in its inner face; connections between the plates, passing through the recesses in 110 the web; a radial slide movable in each radial slot; a slide pivoted to each radial slide and movable in one of the concentric slots; and springs adapted to retain each slide normally in central position in its slot. 115 120
